UNITED STATES PATENT OFFICE.

CARL BUSH, OF MATTOON, ILLINOIS, ASSIGNOR OF ONE-HALF TO FRANK L. WALTERS, OF MATTOON, ILLINOIS.

BEADING-TOOL RETAINER.

1,420,240.

Specification of Letters Patent. Patented June 20, 1922.

Application filed July 16, 1921. Serial No. 485,333.

To all whom it may concern:

Be it known that I, CARL BUSH, a citizen of the United States, residing at Mattoon, in the county of Coles and State of Illinois, 5 have invented new and useful Improvements in Beading-Tool Retainers, of which the following is a specification.

This invention relates to tools, particularly to attachment therefor, and has for its object 10 the provision of a rubber ring adapted to be engaged upon the shank of a beading tool such as is used on boiler flue work for upsetting the ends of the tubes passing through the flue sheet, the purpose of the ring being 15 to prevent the tool from slipping through the operator's fingers and being forced into the tube in the event that the tool should slip off the bead, as frequently occurs. Tools of this character are operated by means of a 20 pneumatic hammer and the tool is held within the fingers of the operator. In case the tool slips off the bead it generally follows that the tool slips through the operator's fingers and has sufficient momentum that it 25 will enter a flue being beaded and become lodged therein so that its removal is impossible even by use of the hook commonly employed for the purpose. The loss of these tools is a very serious source of expense and 30 it is with these facts in view that the present invention has been designed which contemplates the provision of a ring which is calculated to strike against the operator's fingers and prevent the tool from slipping.

35 With the above and other objects and advantages in view, the invention consists in the details of construction to be hereinafter more fully described and claimed and illustrated in the accompanying drawings in 40 which—

The figure shows a perspective view of a beading tool engaged within an operator's hand and showing my retaining ring in position.

Referring more particularly to the drawings, the letter A designates a beading tool of the ordinary well known type which includes a stem B which receives the impact of the pneumatic hammer or which fits into the so-called pneumatic gun, and which further includes the working end C which is used for making the bead upon flues or tubes.

In carrying out my invention I provide a ring 10 of flexible rubber which is slidably engaged upon the tool A but which fits 55 snugly thereon so as not to become accidentally displaced. It is to be noted that this ring is to be placed at any desired point along the tool though in actual practice it is preferable to locate it comparatively near 60 the stem B, as shown in the drawing.

In the use of the tool it will be seen that in case the working end C should slip off a bead being formed the tool cannot slip into the tube or flue as the ring 10 would naturally strike against the operator's fingers and consequently cause the tool to be retained 65 within his hand.

From the foregoing description and a study of the drawing it will be apparent that 70 I have thus provided a very simple and consequently inexpensive retaining device which will efficiently operate to prevent loss of beading tools and which will consequently be a great time and money saver.

Having thus described my invention, I claim:

1. In combination with a beading tool, a ring of flexible material disposed upon the shank of the tool at a selected location and 80 frictionally gripping the tool shank.
2. A retaining device for beading tools adapted to receive impact from a percussion device, comprising a rubber ring disposable upon the shank of a tool and frictionally 85 gripping the same at a desired location.

In testimony whereof, I affix my signature.
CARL BUSH.
